Thomas Mattern
ATTORNEY.

UNITED STATES PATENT OFFICE

RAYMOND G. MOORE, OF BRIDGEPORT, CONNECTICUT, ASSIGNOR TO THE BASSICK COMPANY, OF BRIDGEPORT, CONNECTICUT, A CORPORATION OF CONNECTICUT

HOOD CATCH

Application filed May 23, 1928. Serial No. 279,909.

The present invention relates to automobile hood catches, and has for an object to provide an improved catch of inexpensive construction, having few parts, and which will be positive and effective in securely clamping the hood down and in pressing the same inwardly to prevent looseness and rattling. A further object is to provide a catch in which both the holding down and pressing in actions are functions of the single hood catch spring. A still further object is to provide a hood catch which will compensate for variations in the placement of the catch in relation to the hood, to the end that relatively great manufacturing tolerances will be permitted.

With the above and other objects in view, embodiments of my invention are shown in the accompanying drawings, and these embodiments will be hereinafter more fully described with reference thereto, and the invention will be finally pointed out in the claims.

In the drawings:

Fig. 1 is a side elevation, partly in section, of a hood catch, according to the present embodiment of the invention, showing the same in unhooked or inoperative position.

Fig. 2 is a similar view, showing the same in hooked or operative position.

Fig. 3 is a front elevation, the catch being in the operative position of Fig. 2.

Fig. 4 is a side elevation of a modified form of the invention.

Similar reference characters indicate correspondence parts throughout the several figures of the drawings.

Referring to the drawings, the hood catch, according to the present embodiment of the invention, consists of a cylindrical barrel 10, flanged at its lower end, as at 11, to provide a reduced passage in which a rod 12 is slidably engaged, the end of the rod within the barrel being provided with a fixed washer 13, between which and the flange 11 a spring 14 is coiled about the rod.

The upper end of the barrel is threaded, as at 15, and is secured into the threaded socket 16 of a cap member 17, which closes the upper end of the barrel and forms a stop to limit the upward movement of the rod 12 under the

pressure of the spring. A clamping hook 18, and a handle 19, are formed integrally with the cap members, the hook adapted in the operative relation of the catch, to engage a suitable keeper 20 secured to the side of the hood.

At its lower end the rod 12 is bent inwardly in acute angular relation, as at 21, to provide an inclined cam portion, an upright extension 22 being bent upwardly from the portion 21, and having a bumper or buffer pad 23, secured thereon, adapted in the operative position of the catch to bear inwardly upon the hood, as will presently more fully appear.

The angular portion 21 is slidably and pivotally engaged beneath the transverse cross-piece 24 of a bracket 25, secured to the frame of the automobile, the upright side portions of this bracket being spaced and adapted to restrain the portion 21 against sidewise movement with respect to the cross-piece 24.

In the unhooked or inoperative relation the catch will swing outwardly as shown in Fig. 1, also swinging the bumper outwardly out of contact with the surface of the hood and frame. In hooking the same the spacing of the hook with respect to the bracket 25 is such that the bumper will first engage the hood with the transverse cross-piece engaging the angular portion 21 at a point inwardly of the rod 12, the hook 18 being at the same time engaged with the keeper. The force of the spring thereupon exerts a contracting force on the barrel 10 and rod 12 pulling the hood downwardly and by virtue of the incline of the angular portion 12 camming the catch inwardly so that the bumper exerts a constant inward pressure on the hood.

In Fig. 4 I have shown a modified form of the invention, in which the rod 12 is provided at its lower end with an angularly extending portion 26 having an upwardly inclined slot 27 therein, the cross-piece 24 of the bracket being engaged in said slot. The bumper pad 23 is secured upon an upright extension 28 of the portion 26. The operation is substantially the same as that of the first described embodiment.

I have illustrated and described preferred

and satisfactory embodiments of the invention, but it will be obvious that changes may be made therein within the spirit and scope thereof, as defined in the appended claims.

Having thus described my invention, what I claim and desire to secure by Letters Patent is:—

1. In a hood catch or the like, a member having a keeper engaging hold down clamp, a member longitudinally slidable relatively to said first member, means coacting between and adapted to exert a contracting pressure on said members, said second member having inclined means rigidly connected thereto disposed in inclined angular relation to the longitudinal axis of said member, a fixed support engaged by said inclined means whereby contracting movement of said members is adapted to cause relative inward movement of said inclined means relatively to said support, and side engaging means disposed between the catch and the hood adapted upon said inward movement of the inclined means to exert an inward pressure on the hood.

2. In a hood catch or the like, a member having a keeper engaging hold down clamp, a member longitudinally slidable relatively to said first member, means coacting between and adapted to exert a contracting pressure on said members said second member having an inclined integral extension rigidly connected thereto disposed in inclined angular relation to the longitudinal axis of said member, a fixed support engaged by said inclined extension whereby contracting movement of said members is adapted to cause relative inward movement of said inclined extension relatively to said support, and side engaging means disposed between the catch and the hood adapted upon said inward movement of the inclined extension to exert an inward pressure on the hood.

3. In a hood catch or the like, a member having a keeper engaging hold down clamp, a member longitudinally slidable relatively to said first member, means coacting between and adapted to exert a contracting pressure on said members, said second member having inclined means rigidly connected thereto disposed in inclined angular relation to the longitudinal axis of said member, a fixed fulcrum support with which said inclined means is slidably and pivotally engaged, whereby contracting movement of said members is adapted to cause relative inward movement of said inclined means relatively to said fulcrum support, and side engaging means disposed between the catch and the hood adapted upon said inward movement of the inclined means to exert an inward pressure on the hood.

4. In a hood catch or the like, a member having a keeper engaging hold down clamp, a member longitudinally slidable relatively

to said first member, means coacting between and adapted to exert a contracting pressure on said members, said second member having inclined means rigidly connected thereto, disposed in acute angular relation to the longitudinal axis of said member, a fixed support engaged by said inclined means whereby contracting movement of said members is adapted to cause relative inward movement of said inclined means relatively to said support, and side engaging means disposed between the catch and the hood adapted upon said inward movement of the inclined means to exert an inward pressure on the hood.

5. In a hood catch or the like, a member having a keeper engaging hold down clamp, a member longitudinally slidable relatively to said first member, means coacting between and adapted to exert a contracting pressure on said members, said second member having inclined means rigidly connected at its lower end, a fixed support engaged by said inclined means whereby contracting movement of said members is adapted to cause relative inward movement of said inclined means relatively to said support, and a bumper carrying extension carried by said inclined means adapted upon said inward movement of the inclined means to exert an inward pressure on the hood.

Signed at Bridgeport, county of Fairfield, and State of Connecticut, this 10th day of May, 1928.
